ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SPRING FRICTION CLUTCH.

Application filed November 9, 1925. Serial No. 67,725.

This invention relates to improvements in clutch mechanism particularly useful on the take-ups for narrow ware looms and it is the general object of the invention to provide a mechanism of this type of compact form such that the clutch may be used in a loom weaving a large number of narrow fabrics.

In narrow ware looms it is desirable to place the take-up mechanisms as close as possible so that a large number of fabrics can be woven and it is a further object of my invention to accomplish this result by providing clutches of hollow form for the take-up to accommodate the tensioning springs.

It is necessary occasionally to provide for correcting a mispick by rendering the take-up roll reversible and it is a still further object of my invention to make a clutch for the take-up roll which shall be reversible by the use of a tool forming no permanent part of the take-up mechanism, the tool being thin and of such form as to permit the clutches to be placed close together.

It sometimes happens that after the cloth has been reversed it is necessary to advance the same slightly in order that the fell may be properly placed and it is a still further object of my invention to provide means for advancing the clutch for the take-up roll by means of the same tool employed to effect the reversing of the roll.

It is another object of my invention to provide a clutch having a pair of members each to receive one end of a coiled spring the internal diameter of which is slightly less than the diameter of the constantly rotating shaft on which it is located and to rotate the shaft in such a direction that resistance to the movement of the roll in a forward direction will serve to tighten the grip between the spring and the shaft and thus insure rotation of the clutch.

With these and other objects in view which will appear as the description proceeds, my invention resides in the combination and arrangement of parts hereinafter described and set forth in the claims.

In the accompanying drawings, wherein I have shown a convenient embodiment of my invention,

Fig. 1 is a front elevation of the lower right hand end of a loom showing the take-

up mechanism therefor provided with my improved form of clutch,

Fig. 2 is an enlarged vertical section on line 2—2 of Fig. 1,

Fig. 3 is a vertical section on line 3—3 of Fig. 2, and

Fig. 4 is a detail vertical section through adjacent portions of the clutch members at the ends of the spring locking ring.

Referring to the drawings it will be seen that I have provided a loom side 10 and a breast beam 11. An upper shaft 12 is journaled in the loom side and is connected by means of gear 13 secured thereto to one of a pair of change gears 14 the other of which meshes with a gear 15 secured to the bottom cloth roll shaft 16. The gearing provides means for driving the two shafts 12 and 16 in timed relation with each other but at different rates of speed and one or the other of said shafts is rotated positively by mechanism not shown so that the shaft 12 has an angular motion each pick of the loom to take up the cloth woven. This mechanism illustrates one form of device on which my improved clutch may be used.

My invention relates to the form of take-up clutch associated with the roll and it will be seen by referring to Fig. 1 that I have provided a plurality of driven members 20 shown in detail in Figs. 2 and 3. Each driven member 20 comprises advancing member 21 having a cylindrical surface 22 to cooperate with the work in this instance the cloth W and the member 21 is further provided with a bearing 23 which fits loosely on shaft 12.

Each of said members 20 is formed in part with a reversing disc member 24 loosely mounted on the shaft 12 and having a peripheral groove 25 therein. Said groove has a depth equal to or greater than the diameter of the wire from which is formed spring lock 26 as seen in Figs. 2, 3, and 4. The advancing member 21 is provided with a flange 27 which as shown in Fig. 3 is in substantial alignment with the reversing member 24 and said flange is provided with a groove 28 having a depth approximately one-half the diameter of the wire of which lock 26 is made. As shown in Fig. 2 the periphery of the reversing member 24 is recessed as at 29 to afford access to the indent ends 30 of the lock 26.

As shown in Fig. 4 said ends 30 are sufficiently long to project inwardly beyond the bottom of groove 25 so that any tendency of said lock to crawl will be resisted when either end engages one of the walls of the recess 29. In this way provision is made for keeping the inbent ends 30 in the recess 29 so that they will always be accessible when it is desired to disassemble the take-up roll. 5

10 A coil spring 31 is provided for each member 20 and is so wound that when in normal unexpanded position the internal diameter thereof is slightly less than the diameter of shaft 12 so that the spring will grip said shaft when mounted thereon and be held frictionally against rotary movement on the shaft. Said spring has an extending end 32 which passes through an opening 33 in the reversing member 24 and 15 the other end of said spring is extended as shown at 34 through an opening 35 extending through the web 36 of the member 21. Said web is provided with a threaded hole 37 which receives a locking screw 38 screwed 20 down tightly against the end 34 to prevent disengagement of the spring and member 21.

As shown in Fig. 2 the flange 27 is provided with a plurality of equally spaced 30 openings 39 and the reversing member 24 is provided with a similar set of equally spaced openings 40. For convenience the distance between adjacent holes 39 on the member 21 is equal to the distance between adjacent holes 40 on the reversing member 24, this distance being the same as that between pins P on a tool T as shown in Fig. 2.

In assembling the device the member 21 is slipped onto shaft 12 slightly beyond the 40 position which it is to occupy. The spring 31 is then expanded to increase the diameter of the coils so that they may be slipped over the shaft 12. When the spring is in the proper position it is released to cause 45 the coils to grip the shaft.

Member 21 is then moved toward the spring to cause end 34 of the latter to enter hole 35 and screw 38 positioned to tighten the two parts together. By means of an appropriate tool the ends 30 of the lock 26 are drawn together to cause the lock to be housed entirely in groove 25 of the reversing member, after which the latter is moved into alignment with flange 27 in such 50 a way that end 32 of the spring can enter opening 33. The ends 30 are then released and lock 26 expands to lie partly in groove 25 and partly in groove 28. The member 24 is thus locked against accidental displacement but may be turned with respect to the member 21 without losing contact with spring 31. Thus the member 20 is held against the shaft 12 and rotates with the same. 55

60 When the clutch is applied to the take-up

of a loom and it is desired to make a pick-out it is necessary to release the pressure of the spring 31 against the shaft and reverse the member 20, and in order to accomplish this result pins P of tool T are placed in 70 adjacent openings 40 of member 24 and the tool is given a clockwise movement with respect to the shaft 12 as indicated by arrow R in Fig. 2. The effect of this is to expand the spring 31 and move the same with respect to the shaft 12 in such a direction as to reverse the member 20. If as previously stated it is desired to advance the member 20 to properly position the same the pins of the tool may be inserted in adjacent holes 80 39 as shown in dot and dash lines in Fig. 2 and given a counterclockwise movement as indicated by arrow L. The effect of this is to loosen spring 31 to permit a forward movement of the member 20. 85

From the foregoing it will be seen that I have provided a simple clutch having two operating members which are connected to a third tensioning device in such a way that the clutch can be moved in either 90 direction with respect to the driving shaft by moving one or the other of the members and that the tensioning device grips the driving shaft so that under normal conditions the clutch rotates at the same rate 95 of speed as does the shaft. Also, any resistance offered to the rotation of the member 20 serves only to tighten the grip of the spring 31 against the shaft 12 to insure a greater friction contact necessary to overcome the increased resisting force. 100

Having thus described my invention it will be apparent that changes and modifications may be made therein by those skilled in the art without departing from the spirit and scope of the invention and I do not wish to be limited to the details herein disclosed, but what I claim is:

1. In a clutch mechanism, a shaft having a regular angular motion, a pair of members 110 each loosely mounted on the shaft and independently movable with respect to the other and each provided with a groove concentric with the shaft, said grooves facing and being in alignment with each other, an expansible member normally located partly in one groove and partly in the other to prevent relative movement of the members in the direction of the axis of the shaft, and means to hold said members normally rigid 115 with respect to the shaft to cause said members to move with the shaft. 120

2. In a clutch mechanism, a shaft having a regular angular motion, a pair of members each loosely mounted on the shaft and movable relatively to the other angularly about the shaft, one of said members being driven, means frictionally held to the shaft and slidably thereon when the frictional contact with the shaft is reduced, said 125 130

means being connected to and movable by each member and normally holding both members in fixed relation on the shaft, said driven member being movable in a forward direction with respect to the shaft but held against reverse movement by the means, the other member being held by the means against forward movement with respect to the shaft but movable in a reverse direction to reduce the frictional contact between the shaft and means to effect reverse movement of the member.

In testimony whereof I have hereunto affixed my signature.

ELBRIDGE R. HOLMES.
